CLAIM

The ornamental design for a cart for pots, pans, lids and other kitchen utensils, as shown and described.

DESCRIPTION

FIG. 1 is a front perspective view of a cart for pots, pans, lids, and other kitchen utensils showing my new design.

FIG. 2 is a front elevation view thereof.

FIG. 3 is a section view thereof, taken along the lines 3—3 of FIG. 2.

FIG. 4 is a top plan view partially in section thereof, taken along the lines 4—4 of FIG. 2.

The bottom and rear of the cart are understood to be flat and unornamented.
